UNITED STATES PATENT OFFICE.

IRVING A. MCKINLEY, OF CICERO, NEW YORK.

PORTABLE TOBACCO-PRESS.

SPECIFICATION forming part of Letters Patent No. 401,448, dated April 16, 1889.

Application filed April 12, 1888. Renewed January 31, 1889. Serial No. 298,253. (No model.)

To all whom it may concern:

Be it known that I, IRVING ALEXANDER MCKINLEY, of Cicero, in the county of Onondaga and State of New York, have invented 5 a new and Improved Portable Tobacco-Press, of which the following is a full, clear, and exact description.

My invention relates to an improved portable tobacco-press, and has for its object to 10 provide a press especially adapted for packing leaf-tobacco in boxes for shipment, which may be quickly applied to and detached from the box or case.

The invention consists in the construction 15 and combination of the several parts, as will be hereinafter fully set forth, and pointed out in the claims.

Reference is to be had to the accompanying drawings, forming a part of this specification, 20 in which similar letters of reference indicate corresponding parts in all the figures.

Figure 1 is a plan view of a box having my press applied. Fig. 2 is a central vertical section through the same on line $x-x$ of Fig. 25 1. Fig. 3 is an end view, and Fig. 4 a section on line $y-y$ of Fig. 2.

It is the prime object of the present invention to provide a press simple in construction and operation, and of moderate cost, 30 specially adapted for use by farmers for pressing tobacco as it is assorted. It is customary for the farmers to make four or more grades, and as a case is provided for each grade the tobacco is pressed in each case alternately.

35 When the present presses are applied to or removed from a case for application to another, a great deal of lifting and manipulation of the boxes or cases is necessary, greatly adding to the labor of marketing the leaf. To overcome this disadvantage, I construct a board, A, which I designate a "bottom" board, preferably rectangular in shape, of a length greater than the width of the box or case to be packed, and upon the upper face 40 of said bottom board at the extremities a hook, a , a ring, snap, or equivalent device is attached. An upper board, B, is also provided, preferably of a length and general contour similar to the bottom board, which 45 upper board has attached to each extremity a length of chain, D, adapted for attachment to the hook or ring of the bottom board.

Near the ends of the upper board essentially U-shaped metal rests or foot pieces C are

adjustably attached by set-screws C', or their equivalents, the purpose of which rests is to engage the edges of the box and prevent tipping of the upper board. As a ready means of attaching the rests, recesses are made in the side edges of the top board, which 60 recesses are covered by metal straps C², the set-screws C' passing through the strap, as shown in Fig. 4. A central threaded aperture is produced in the upper board to receive a screw, E, which screw below the board is 65 made to bear upon a press plate or follower, E', of a size adapted to the interior of the box or case, and at the upper end of the screw a hand wheel or bar, E², is secured. Thus by placing a bottom board beneath each case in 70 which the tobacco is to be pressed, the follower need only be inserted and the chain of the top board attached to the hook or eye of the bottom board, and the press is ready for operation. By this means the boxes or cases 75 need not be handled until fully packed and ready for transportation.

The rests need be used only when the box has been packed to a point near the top. Then they are pressed downward to an engagement 80 with the side edges of the box and secured. By this means the top board may be elevated above the upper end of the box and at the same time be held from tilting.

Having thus described my invention, what I 85 claim as new, and desire to secure by Letters Patent, is—

1. The combination, with an upper board provided with rests, a screw passing through said upper board, and a follower engaging the 90 lower end of said screw, of a bottom board and a detachable link-connection between the ends of the said upper and lower boards, substantially as and for the purpose herein set forth.

2. The combination, with an upper board 95 provided with adjustable essentially U-shaped rests, a screw passing centrally through said board, having a hand-hold at the upper end, and a plate or follower engaging the lower end of the screw, of a bottom board 100 having eyes attached at the ends and a chain secured to the ends of the upper board and detachably engaged with said eyes, substantially as and for the purpose herein set forth.

IRVING A. MCKINLEY.
